[57] CLAIM

The ornamental design for a hook fastener for the waist bands of trousers or the like, substantially as shown and described.

DESCRIPTION

FIG. 1 is a front elevational view of a hook fastener for the waist band of trousers or the like showing my new design;

FIG. 2 is a rear elevational view thereof;

FIG. 3 is a top plan view thereof; the showing of a portion of garment in broken lines is for illustrative purposes only;

FIG. 4 is a right side elevational view of the hook fastener;

FIG. 5 is a right side elevational view of the eye;

FIG. 6 is a left side elevational view of the hook fastener;

FIG. 7 is a left side elevational view of the eye; and
FIG. 8 is a top plan view of the hook fastening for the waist bands of trousers or the like in operative condition; the broken lines are for illustrative purposes only.

FIG. 1

FIG. 2

FIG. 8

FIG. 3
